COMMUNICATION SYSTEM

Robert F. Davis, Washington, D. C.

Application January 14, 1939, Serial No. 251,027

2 Claims. (Cl. 179—1)

This invention relates to a system of communication particularly adapted for conversation between three or more stations, and so arranged as to afford a maximum degree of control 5 of the system at each of the stations.

Prior to this invention there were two systems of what is known as "inter-office communication" in common use. One of these systems includes a master unit which has complete control and a plurality of sub-station units which exercise no control whatever. The other type of system consists of a plurality of master station units, each of which possesses a certain amount of control over the system.

15 In the first mentioned system the master unit includes a loud speaker which acts also as a microphone, an amplifier, and certain switching mechanism which permits the operator to connect his unit to any one of the sub-station units in either one of two ways. If he wishes to talk to the sub-station, which sub-station consists merely of a loud speaker which will also act as a microphone, he connects the loud speaker at the master station to the input of the amplifier 20 at that station and the output of the amplifier at that station to the loud speaker at the sub-station. When he wishes to listen to someone at the sub-station he merely reverses the connection and is thus enabled to hear the signals 25 which are picked up by the loud speaker at the sub-station, amplified, and reproduced by the loud speaker at the master station.

In the other type of system in which all of the stations are of the master type, each unit 30 has a pair of wires which constitute its normal or primary circuit, one of which wires may be a common or ground wire. These wires are normally connected to a loud speaker-microphone at that station. The operator at each of the other stations is then able to connect his loud speaker-microphone into the input of his amplifier and connect his amplifier to the primary circuit of any other station to which he wishes 35 to speak. Having conversed, it is necessary for him to break these connections and put his speaker back on its normal or primary circuit, after which the operator at the station to which he has spoken may reply by making the necessary connections, that is, placing the loud speaker 40 at the replying station in the input circuit of the amplifier at the replying station and connecting the output of the amplifier at the replying station to the normal circuit of the station to which the reply is directed.

45 The use of the first arrangement described

above involves a difficulty in that the sub-station operators can exercise no control over the system, cannot talk to the master station except when the master station is connected to listen to them and cannot talk to each other. The second system has the disadvantage that it is necessary for the operator at a station that is called to be told the number or name of the station calling him, and then, for this same operator to manipulate the switches on his box in order to 5 reply. If it so happens that the electric power is turned off at the station that is being called, it then becomes impossible for the operator at that station to reply until he has turned on the electric current and allowed the vacuum tubes 10 in the amplifier to become heated.

To overcome these difficulties the present invention provides a system which may include all master station units, each of which can exercise a relatively complete control over the system, or 20 may include with one or more master station units, one or more sub-station units which can receive a message from any one of a plurality of master stations and can transmit a reply, but which can exercise no control over the system. 25

According to this invention an operator at any one of the master station units can initiate a conversation through any one of the stations to which he has a connection, whether it be a master station or a sub-station, and can carry 30 on a two-way conversation with the operator at any one of these stations under his own complete control, without the necessity of any action on the part of the operator at the called station, and regardless of whether or not the electric 35 power at the called station is turned on. Since the operator at the called station does not need to manipulate his unit, it is not necessary to tell the operator at that station the name or number of the station calling, and it is unnecessary for 40 that operator to come to the station if he happens to be some little distance from it, for he may simply reply to the voice heard through his station from anywhere in proximity thereto.

The present system also combines a feature 45 which enables the operator of any master station to ascertain whether or not the station to which he wishes to communicate is busy in another conversation, and a feature which will prevent eavesdropping without preventing a call from being received should one be made.

The new system comprises essentially a plurality of stations, each of which includes a receiver-microphone and at least two of which also include an amplifier and certain switching devices. 55

A primary circuit is provided for each station in which the receiver-microphone of that station is normally connected and the switching devices are arranged so that at one position they disconnect the receiver-microphone at that station from its primary circuit and connect it to the input of the amplifier at the same station and at the same time connect the output of the amplifier to the primary circuit of any other selected station. This enables the operator to talk to any selected station. At another position this switching means connects the primary circuit of another station to the input of the amplifier at its own station, disconnects the receiver-microphone at its station from its normal primary circuit and connects this receiver-microphone to the output of the amplifier. This enables the operator to receive a message from any selected station.

In addition to this mechanism, the system may also be provided with means operative to indicate the reception of the signal which will not act as a microphone and which is arranged to be connected into the primary circuit in lieu of the receiver-microphone of the particular station. This exchange need be made only when a confidential conversation is being carried on in the neighborhood of the station and it is desired that eavesdropping be prevented.

A consideration of the following description of one embodiment of the new system will furnish a detailed understanding thereof and an example of the principles involved therein. In connection with this description, reference should be had to the accompanying drawing in which:

Fig. 1 is a diagrammatic illustration of the preferred form of the system; and

Figs. 2 and 3 are diagrammatic illustrations of one of the switches showing positions that it may assume.

In the system illustrated in Fig. 1, there is shown diagrammatically two master stations A and B and a sub-station C. Each station has a receiver-microphone 11 which acts both to change electrical impulses into sound and to change sound back into electrical impulses, depending upon the manner in which it is connected in the circuit. Station C consists only of the receiver-microphone, which is connected on one side to a ground and on the other to the normal or primary circuit 12 of that station. Each of the master stations A and B includes in addition to the receiver-microphone 11, an amplifier 13, a talk-listen switch 14, which is shown in Fig. 1 in its normal or inactive position, and a selector switch 15 which is used to select the station to which a connection is to be made. In addition there is provided at each of the master stations A and B an annunciator 16 or a receiver that will not act as a microphone, which can be used in lieu of the receiver-microphone 11 to prevent eavesdropping and yet announce the fact that the station is being called. This device is connected alternatively into the same circuit as is the receiver-microphone 11 by means of a switch 17. As may be seen from Fig. 1, when the switch 17 is operated to connect one or the other of the receiving devices 11 and 16 into the circuit, that device is then connected, if the talk-listen switch 14 is in its normal position, to an outgoing wire from the station, which wire will hereafter be referred to as the normal or primary circuit 18 of station A and as the normal or primary circuit 19 of station B.

As has been stated, the talk-listen switch 14 is shown as in its normal or inactive position in

Fig. 1. It is shown again in Figs. 2 and 3 in its listen and talk positions respectively. As can be seen by a study of these figures, when the operator at station A, for example, desires to initiate a conversation with the operator at station B, and assuming that his own amplifier is in operation and his own switch 17 is connecting his own receiver-microphone 11 into the circuit, he need only perform the following operations. First, he turns his selector switch 15 to the primary circuit 19 of station B. Next, he turns his talk-listen switch 14 to the talk position shown in Fig. 3, by which action the receiver-microphone 11 at station A is disconnected from its normal circuit 18 and inserted in the input circuit of the amplifier 13 at station A and the output of the amplifier 13 is connected to the normal primary circuit 19 of station B, which in turn connects either to the receiver-microphone 11 of that station or to the annunciator device 16 of that station. If the connection is to the receiver-microphone of station B, the voice of the operator at station A will be heard when he speaks into his own receiver-microphone, and if the connection is to the annunciator 16, that device will operate either when the output of the amplifier of station A is connected to it or when the operator at station A speaks into his receiver-microphone. If the operator at station B has the annunciator 16 connected in lieu of his receiver-microphone, he must change the connection; otherwise he need do nothing but reply. When the operator at station A has completed his message to the operator at station B he turns his switch to the listen position shown in Fig. 2, at which time he is enabled to hear the reply of the operator at station B by reason of the fact that the receiver-microphone 11 at that station is connected through the normal or primary circuit 19 of that station and the selector switch 15 of station A and the talk-listen switch of that same station to the input of the amplifier at station A, the output of which is connected through the same talk-listen switch to the receiver-microphone at station A. As the amplifier 13 at station B is not used in this process it is not even necessary that it be in operation during a conversation initiated and controlled by the operator at station A. If, however, the operator at station B wishes to initiate and control the conversation, he may do so in exactly the same manner as did the operator at station A but in that event it will be necessary that his amplifier be operating. The operator at station C is in exactly the same position as the operator at station A or B when their particular amplifier is not operating. He can receive messages and respond when he is called but is unable to initiate any calls or to control the conversation.

It will be obvious to those skilled in the art that the form of the switches and particularly of the talk-listen switch may be varied according to individual taste and expediency and that the particular type of receiver-microphone, amplifier, or annunciator are not important insofar as the functioning of the system is concerned. It is only necessary that they be capable of performing the functions allotted to them. For example, the annunciator may be a loud speaker of a type that will not act as a microphone or it may be merely an annunciator that will not reproduce speech at all. The switch 17 that connects this annunciator in the circuit may be biased so that it will normally tend to keep either

the annunciator or the receiver-microphone in the circuit, whichever is preferred.

I claim:

1. A system for intercommunication that comprises a plurality of stations each of which includes a receiver-microphone and at least two of which also include an amplifier and switching means, and a primary circuit for each station in which the receiver-microphone of that station is normally connected, the switching means being arranged so as at one position to disconnect the receiver-microphone of its station from its primary circuit, connect the said receiver-microphone to the input of the amplifier at its station and connect the output of the amplifier to the primary circuit of another

station, and at another position to connect the primary circuit of another station to the input of the amplifier at its station, disconnect its receiver-microphone from its primary circuit and connect the said receiver-microphone to the output of said amplifier. 5

2. A system as described in claim 1 in which a device that will indicate the reception of a signal but will not act as a microphone is arranged to be connected in the primary circuit 10 at at least one of said stations, in lieu of the receiver-microphone during periods when the station is not in active operation, so as to prevent eavesdropping but announce the fact when the station is called. 15
